UNITED STATES PATENT OFFICE.

HENRY A. SCHMIDT, OF LONG ISLAND CITY, NEW YORK.

CONVERTIBLE BED-SPRING.

1,398,203.

Specification of Letters Patent. Patented Nov. 22, 1921.

Application filed February 19, 1921. Serial No. 446,423.

To all whom it may concern:

Be it known that I, HENRY A. SCHMIDT, a citizen of the United States, residing at Long Island City, in the county of Queens 5 and State of New York, have invented certain new and useful Improvements in Convertible Bed-Springs, of which the following is a specification.

This invention has relation to furniture, 10 and has for an object to provide a bed spring which is so constructed as to be convertible from a flat reclining support to an inclined support having seat, back and leg rest portions so that the occupant may rest thereon 15 in a semi-upright position.

Another object of the invention is to provide a convertible bed spring of the character mentioned which consists of a main frame adapted to rest in an ordinary bed 20 frame and having auxiliary spring frames mounted thereon in pivoted relation and adapted, when in alinement to form a flat reclining surface, or when adjusted at relative angles to form a seat portion, back and leg 25 rest.

In addition to the foregoing this invention comprehends improvements in the details of construction and arrangement of parts to be hereinafter described and particularly set 30 forth in the appended claims.

In the accompanying drawings in which similar and corresponding parts are designated by the same characters of reference throughout the several views in which they 35 appear,

Figure 1 is a view in perspective of a convertible bed spring constituted in accordance with my invention.

Fig. 2 is a view thereof in side elevation 40 showing the parts in alinement to form a flat surface.

Fig. 3 is a similar view showing the parts positioned to form an inclined surface.

Fig. 4 is a view in side elevation of the 45 auxiliary back rest.

Fig. 5 is a view in side elevation of one main frame bar.

Fig. 6 is a view in side elevation of the leg rest frame.

Fig. 7 is a view in side elevation of the 50 seat frame.

Fig. 8 is a view in perspective of a frame supporting bracket.

Fig. 9 is a view in side elevation of the 55 actuating lever.

Fig. 10 is a view in side elevation of a link.

Fig. 11 is a view in side elevation of an adjusting screw.

With reference to the drawings, 10 indicates the longitudinal members of the main frame, formed preferably of angle iron, and which are connected at one end by means of the bar 11. Located at one end of the main frame is an auxiliary frame or back 60 rest frame consisting of the side bars 12 connected at one end by the bar 13 and having their opposite ends bent at right angles to form the offset portions 14. The latter are pivoted to the side bars 10 intermediate the 65 ends thereof. Another auxiliary frame termed the seat frame is provided consisting of the side members 15, one end of each of which is pivotally connected to the ends of the bars 12 at the point of flexure of the portions 14. A third auxiliary frame is provided termed the leg rest frame and consisting of the side bars 16 connected at one end by means of the bar 17 and having their opposite ends bent to form offset portions 18, the 70 extremities of which are connected to the ends of the main frame bars 10, and the points of flexure connected to the terminals of the bars 15. These connections are made to the inner sides of the bars 10 and 15. To 75 reinforce these parts I provide links 19 which pivotally connect the ends of said bars 10 and 15 but contact with the outer faces thereof. An actuating lever 20 is provided which is pivoted at one end 80 to the main frame member 10 on a point between the offsets 14 and 18 while its other end is pivoted to the frame member 15 by means of a bolt 21 which may be tightened or loosened at will. The extremity of 85 the lever is reduced to receive a removable handle 22. The auxiliary frames are all covered with spring supported reticulated material in the conventional manner as indicated at 23 to form a supporting surface, and sections of mattress 24 are supported upon the auxiliary frames. A fourth frame 90 25 covered with reticulated material may be provided to form a foot rest and is formed with bent terminals 26 which are apertured 100 to receive set screws 27 which penetrate 105 tapped openings in the frame bars 16.

For use as a bed the auxiliary frames are disposed in horizontal alinement as shown in Fig. 2, the offsets 14 and 18 being vertical. 110

The bars 12 will be supported upon brackets 28 which are mounted upon the main frame bars 10 and which are formed with bifurcated upper terminals to embrace the bars 12. 5 To convert the device into a reclining chair the bolt 21 is loosened and the lever 20 moved forward. This may be done by the occupant while resting upon the bed and without arising. The auxiliary frames will 10 now move forward and owing to the offsets the back frame will tilt up at an angle and the leg rest frame will tilt downward at a corresponding angle, the intermediate frame maintaining a horizontal but slightly lowered position. When the proper angle has 15 been attained the bolt 21 is again tightened which will maintain the parts in position. If desired a screw 29 may be mounted upon the under side of the seat frame to engage 20 a complementary part mounted on the main frame so that the frames may be adjusted by rotation of the screw and thus be held positively in all positions. A socket member 30 is mounted on each side of the seat frame to receive the supporting standard 31 of a table 25 32, the latter being thus removable when desired.

From the foregoing it will be seen that I have provided a novel apparatus which may 30 be supported in a bed frame of any conventional form in place of the ordinary bed spring to permit invalids to elevate themselves to a reclining position during the day 35 time and to restore the functions of a bed for the night. This device may be made on a small scale for embodiment in babies cribs. Other uses and advantages will readily occur to those familiar with the art to which this invention appertains.

40 While I have illustrated and described my

invention with some degree of particularity I realize that in practice various alterations therein may be made. I therefore reserve the right and privilege of changing the form of the details of construction or otherwise 45 altering the arrangement of the correlated parts without departing from the spirit of the invention or the scope of the appended claims.

Having thus described my invention what 50 I claim as new and desire to secure by United States Letters Patent is:—

1. A convertible bed spring including a main frame, an auxiliary frame having angular offset terminals pivoted to the main 55 frame, a second auxiliary frame having offset angular terminals also pivoted to the main frame, and a third auxiliary frame pivotally supported upon and between the first and second frames.

2. A convertible bed spring including a main frame, a back rest frame including side bars, right angular portions on said side bars pivoted to the main frame, a leg rest frame including side bars, right angular portions on said side bars pivoted to the main frame, and a third set of side bars 65 pivotally connecting the right angular portions of said frames.

3. A convertible bed spring including a 70 main frame, back rest and leg rest spring frames pivoted thereto, a seat spring frame supported between said first mentioned frames, and a lever pivoted to the main frame and to the seat frame adapted upon 75 oscillation to move said auxiliary frames relative to the main frame.

In testimony whereof I affix my signature.

HENRY A. SCHMIDT. [L.S.]
